ROTOR FOR CENTRIFUGAL STILLS

Eric K. McLean and Russell H. Ives, Rochester, N. Y., assignors, by mesne assignments, to Eastman Kodak Company, Rochester, N. Y., a corporation of New Jersey

Application February 21, 1947, Serial No. 730,126

3 Claims. (Cl. 202—205)

1

This invention relates to an improved apparatus for vacuum distillation of thermally decomposable substances while in the form of a thin film and particularly to a rotating vaporizing surface which will have uniform temperature.

It is well known in the vacuum distillation art to subject thermally decomposable substances to vacuum distillation while in the form of a thin film. In the centrifugal stills of the past this has been accomplished by introducing a stream of work liquid at a point near the center of a rotating, heated, thin metal plate. Centrifugal force acting on the liquid spread it out in a thin film and the heat transfer from the metal plate to the liquid effected the vaporization of the lighter, easily vaporized constituents. The liquid flowed rapidly to the periphery of the rotating plate where the residue was collected in gutters. See Hickman Patents 2,210,928; 2,308,008; 2,343,667; 2,349,431; and 2,408,639. Since the liquid was in contact with a hot surface for a very short time thermal decomposition was reduced to a minimum. There was, however, some thermal decomposition as evidenced by a loss of as much as 33% of the vitamin A when concentrating it from a fish liver oil in a centrifugal high-vacuum unobstructed-path still.

This invention has for its object to avoid a portion of the decomposition which takes place in centrifugal high-vacuum unobstructed-path distillation. Another object is to provide an improved vaporizing surface for a centrifugal, high-vacuum, unobstructed-path still. A further object is to provide a vaporizing surface for a centrifugal, high-vacuum, unobstructed-path still in which the surface temperature is nearly uniform at all points. Another object is to improve the state of the art. Other objects will appear hereinafter.

These and other objects are accomplished by our invention which includes vacuum distillation apparatus wherein a rotatable vaporizing surface is constructed in comparatively thick form of a metal of high thermal conductivity. Comparatively massive construction, for example, heavy construction considerably in excess of the scale required in order for the rotor to have sufficient structural strength to function without breakdown, provides a metal heat reservoir which gives the rotor, or vaporizing surface, a more uniform surface temperature than is the case where a thin metal rotor is used. By constructing the rotor of a metal of high thermal conductivity such as aluminum, copper, silver, gold, or magnesium, or various plated combinations of such

2

metals, a method is provided whereby any variation in rotor surface temperature is quickly erased by the flow of heat.

In the following description we have given several of the preferred embodiments of our invention but it is to be understood that these are set forth for the purpose of illustration and not in limitation thereof.

In the accompanying drawing, wherein like numbers refer to like parts, we have illustrated several of the preferred embodiments of our invention wherein:

Fig. 1 is a partial top view of the rotor shown in cross section in Fig. 2. Fig. 2 is a sectional view of a rotor used in a small centrifugal still. Fig. 3 is a sectional view of a cup-shaped rotor of a type used in a large centrifugal still.

Referring to Figs. 1, 2, and 3, numeral 10 designates the flat area on which work liquid (not shown) is introduced. Numeral 11 designates the area from which vaporization takes place. Numeral 12 designates the center hole which is used to secure the rotor to the shaft (not shown) on which it rotates.

25 In operation a rotor in a centrifugal still is rotated by a shaft attached at hole 12. The heating element underneath the rotor is placed in operation. The liquid to be distilled is introduced at the flat area 10 and centrifugal force 30 drives it over the vaporizing area into collecting gutters.

In the past rotors were made of aluminum or steel spinnings. A thin sheet of metal was attached to a wood or metal chuck of the shape 35 desired for the rotor. The chuck was then rotated and a tool held against the spinning metal until it conformed to the contours of the chuck. A very thin sheet of metal was used as it was easy to work into shape and offered less resistance to the flow of heat from the heating element located beneath the rotor.

With the use of rotors composed of aluminum or steel spinnings there was a loss of approximately 33% of the vitamin A when it was concentrated from fish liver oils. This loss was caused by thermal decomposition but it was thought that such a loss was inherent in the operation of the still.

We have produced a rotor which has reduced 50 the vitamin loss caused by thermal decomposition to approximately 16%. We have done this by constructing the rotor of massive metal of high thermal conductivity such as magnesium, aluminum, copper, silver, and gold. We have made our new rotors thicker and heavier than

the spinnings formerly used. By this design the heat radiated from the electric heating element underneath the rotor to the rotor is spread evenly and quickly to the surface of the rotor. Local overheating of the rotor surface is restricted and thermal decomposition is thus reduced to a minimum.

The coefficient of thermal conductivity is usually expressed as the B. t. u.'s which will flow through a cubic foot of the metal in an hour where the temperature differential on two opposing sides is 1° F. The coefficient varies slightly at various temperatures. The following table of thermal conductivity coefficients at 212° F. is from the Chemical Engineers' Handbook, John H. Perry, 2nd edition, page 949.

Aluminum	119
Copper	218
Silver	238
Gold	170
Magnesium	92

We have found that rotors constructed of metals in the above group are satisfactory. Where the coefficient of thermal conductivity of the metal of which the rotor is constructed is below the coefficient for magnesium there is less opportunity for the heat to flow uniformly over the surface of the rotor, and thermal decomposition of the distilland increases. The higher the coefficient the more satisfactory the metal for use in rotor construction.

We have found that a thick rotor gives less thermal decomposition of distilland than a thin one. Performance improves with thickness but we have had satisfactory results from a thickness of as little as $\frac{1}{16}$ ". Above $\frac{1}{16}$ " in thickness the performance is still further improved but the added resistance to heat flow necessitates heating units of larger capacity thus increasing power costs.

Where extremely large rotors are used, e. g. 10 ft. diameter, the rotor thickness at the vaporizing surface will be as much as 1½ inches, that is, the ratio of the thickness to the diameter is 1/80. In a medium-size rotor, e. g. 30 in. diameter, we prefer to operate with a rotor thickness within the range of $\frac{1}{4}$ "- $\frac{1}{2}$ ", that is, a thickness to a diameter ratio of from $\frac{1}{120}$ to $\frac{1}{60}$.

The method of fabrication is not important. Castings and forgings are equally satisfactory and other methods of fabrication would produce suitable rotors.

Combinations of metals of high thermal conductivity may be used. For example, copper is a very desirable material of construction but it has a destructive effect upon certain vitamins. Silver is a desirable material of construction but it is expensive. A rotor constructed of copper with a silver coating would be comparatively inexpensive and would have excellent performance characteristics.

Alloys may be used provided their coefficient of thermal conductivity is sufficiently high. An alloy with a coefficient of 90 (B. t. u./hr.) (sq. ft.) (°F. per ft.) or better would be substantially as effective as magnesium.

The following table shows the improved yield of vitamin A concentrate from fish oil when a $\frac{3}{4}$ inch aluminum rotor was used instead of a $\frac{1}{16}$ inch steel rotor. The tests of both aluminum and thin steel rotors were run in two 5-foot stills and the figures given are in each case the average for 3 distillations.

The ratio of the thickness to the diameter of the $\frac{3}{4}$ inch thick, 5 foot diameter aluminum rotor was thus 1/80.

	Steel Rotors	Aluminum Rotors
Still input, Vitamin A units per gram	13,990	12,670
Concentrate, Vitamin A units per gram	189,000	177,710
Concentration Factor (conc. output) (conc. input)	13.5	14.0
Vitamin A Per Cent Recovery Concentrate	63.4	80.6
Residue	3.7	3.7
Total	67.1	84.3

The surface area was the same for both the steel and aluminum rotors used in the test but the aluminum rotor was thicker.

In concentrating vitamin A from fish oils on an aluminum rotor the loss is approximately 16% as opposed to a 33% loss on a steel rotor. Other improvements are decreased power consumption, less vibration, reduced and more uniform charing on the distillation surface, and easier cleaning. The concentrate is of improved quality and is sufficiently bland to use in margarine fortification.

What we claim is:

1. In a centrifugal vacuum still apparatus especially effective for distilling large volumes of thermally decomposable material, an aluminum rotor at least 30 inches in diameter and having a wall thickness in the region of the vaporizing surface at least $\frac{1}{120}$ of the diameter of the rotor, which thickness is substantially greater than the wall thickness necessary for structural strength.

2. In a high vacuum unobstructed path centrifugal still especially effective for distilling thermally decomposable material, an aluminum rotor having a diameter of 30 to 120 inches and a wall thickness in the region of the vaporizing surface of $\frac{1}{120}$ to $\frac{1}{60}$ the diameter of said rotor with the minimum thickness being not less than $\frac{1}{4}$ inch and the maximum thickness not more than 1½ inches, which wall thickness is substantially greater than the wall thickness necessary for structural strength of said rotor.

3. In a centrifugal vacuum still apparatus especially effective for distilling thermally decomposable material, a cast aluminum rotor having a diameter not less than about 60 inches and a wall thickness in the region of the vaporizing surface of at least $\frac{1}{120}$ the diameter of said rotor, which thickness is substantially greater than the wall thickness necessary for structural strength.
